CLAIM

The ornamental design for a fan heater, as shown and described.

DESCRIPTION

1.-2. Fan heater

1.1 : Front

1.2 : Back

1.3 : Left

1.4 : Right

1.5 : Top

1.6 : Bottom

1.7 : Perspective

1.8 : Front view of component 1

1.9 : Left view of component 1

1.10 : Right view of component 1

1.11 : Top view of component 1

1.12 : Front view of component 2

1.13 : Left view of component 2

1.14 : Top view of component 2

2.1 : Front

2.2 : Back

2.3 : Left

2.4 : Right

2.5 : Top

2.6 : Bottom

2.7 : Perspective

Back and bottom views of component 1 are omitted as they are the same as back and bottom views of the combination (i.e. reproductions 1.2 and 1.6) respectively; back, right and bottom views of component 2 are omitted as they are the same as front, left and top views of component 2 (i.e. reproductions 1.12-1.14) respectively.

1 Claim, 21 Drawing Sheets
